UNITED STATES PATENT OFFICE.

FERDINAND TUREK, OF CLEVELAND, OHIO.

BEER-COOLER.

1,077,016.

Specification of Letters Patent.

Patented Oct. 28, 1913.

Application filed December 12, 1911, Serial No. 665,204. Renewed February 17, 1913. Serial No. 749,027.

To all whom it may concern:

Be it known that I, FERDINAND TUREK, citizen of the United States, residing at Cleveland, in the county of Cuyahoga and State of Ohio, have invented certain new and useful Improvements in Beer-Coolers, of which the following is a specification.

This invention relates to beer coolers, refrigerators and the like, and especially to a device for maintaining water at a certain height in the cooler.

It is designed as an improvement of the invention shown in my Patent No. 1,085,923, granted to me Aug. 20, 1912.

The object of the invention is to provide improved means for regulating the outflow of waste water resulting from the melting of ice in the cooler, the intent being to maintain the water in the lower part of the cooler, at a desired depth.

The invention is illustrated in the accompanying drawings in which—

Figure 1 is a sectional view of a cooler box. Fig. 2 is a detail in vertical section of the adjustable waste outlet.

Referring specifically to the drawings, 6 indicates the box of the cooler and 7 are the beer inlets to the cooling coils 9.

8 is a perforated plate or false bottom for supporting the ice.

18 is a waste pipe leading to the sewer or otherwise. The mouth of this pipe is provided with a removable pipe section 11 which is tapered at the bottom to form a plug fitting in the hole in the bottom of the box, leading to the waste pipe. Packing 17 makes the plug water tight.

12 is an adjustable pipe section which slides up and down in the pipe 11, with a water tight joint produced by the packing 13. The pipe 12 has at the top a flange 19 to prevent it dropping down too far and to enable it to be grasped to be easily raised and lowered.

45 10 is a casing or sleeve surrounding the pipe 12. This is mounted at its lower end on the pipe 11, so that it will remain in position thereon, the bottom having holes 16 to permit inflow of water. The top has holes 50 14 and also serves to prevent pieces of ice dropping into the shell 10. A pipe 15 is supported in the top of the casing 10, in po-

sition above the pipe 12, and this pipe 15 may be connected to a drip pipe from the drippings pan 30 in the top of the counter or 55 bar or otherwise arranged to receive the drippings from the bar.

In order for water to escape from the box it must flow into the casing 10 and then down through the pipes 12 and 11, and obviously the height of water will be controlled by the height or adjustment of the pipe 12. This may be regulated as desired, and as the water rises it will overflow into the pipe 12 and thence out to waste. The 60 65 bar drippings through the pipe 15 will also drop into the waste pipe. Owing to the continual flow of water through the outlet devices the tendency of the pipes to become coated or clogged with slime from the bar 70 drippings will be avoided, and small pieces of ice cannot enter and clog the outlet. By lifting the device and pulling out the plug at the bottom of the pipe 11 all the water in the box may be run off to waste. 75

What I claim is:

1. An outlet device for beer coolers or the like, comprising an outlet pipe located in the bottom of the cooler and leading to a waste pipe therefrom, a perforated casing 80 surrounding said pipe and having a top covering the upper end thereof, and a drippings pipe supported by the top of said casing and arranged to discharge into said pipe. 85

2. The combination with the box of a beer cooler or the like, and a waste outlet in the bottom thereof, of a lower pipe section having a plug fitting in said outlet, an upper pipe section mounted on the lower pipe section and adjustable vertically to govern the depth of water in the box, a perforated casing surrounding said sections, and a drippings pipe extending through the top of said casing, and supported thereby in position to discharge into said adjustable section. 90 95

In testimony whereof I do affix my signature in presence of two witnesses.

FERDINAND TUREK.
